UNITED STATES PATENT OFFICE.

CLARENCE A. BUCHHOLZ, OF BEREAL, OHIO.

CONCEALED TROUSERS-SUPPORT.

1,367,235.

Specification of Letters Patent.

Patented Feb. 1, 1921.

Application filed October 22, 1919. Serial No. 332,401.

To all whom it may concern:

Be it known that I, CLARENCE A. BUCHHOLZ, residing at Berea, in the county of Cuyahoga and State of Ohio, have invented 5 certain new and useful Improvements in Concealed Trouser-Supports, of which the following is a full, clear, and exact description, reference being had to the accompanying drawings.

10 This invention relates to a trouser support of the suspender type.

An object of the invention is to provide a trouser support that will be more healthful than the ordinary tight belt in the absence 15 of a vest, and yet avoid the objection to the ordinary suspenders in that it is entirely concealed under the shirt of the wearer.

Another object is to provide such a device 20 that will prevent the shirt working upward, as well as support the trousers. Other objects are the provision of a supporting means that is simple, strong, and adapted to be readily applied and removed.

My invention is hereinafter more fully 25 described and is illustrated in the accompanying drawings. The essential features are summarized in the claims.

In the drawings, Figure 1 illustrates in dotted lines the support embodying my invention as it would appear under the shirt 30 of the wearer; Fig. 2 is a perspective view of the end of one of the supporting webs showing one of the coöperating attaching members secured thereto; Fig. 3 is a perspective of a second attaching member; Fig. 4 is an elevation of the inside waistband of 35 the trousers showing the third attachment member secured thereto, and Fig. 5 is a vertical section through the point of attaching 40 of the support to the shirt and waistband of the trousers, showing the parts in assembled position.

Referring to the drawings, the numeral 10 designates the webs of a trouser support. 45 These consist of two narrow strips of fabric, elastic or otherwise as desired, which extend over the shoulders of the wearer and are preferably crossed in the back. Each of the ends of the webs or braces is secured to the 50 shirt and trousers in a similar manner at properly spaced intervals around the waist by the means illustrated in the drawings generally at 12.

My improved attaching means is shown 55 in detail in Figs. 2 to 4, and in assembled

engagement in Fig. 5. As will be apparent it consists of three parts, a member 15 secured to the end of the web or brace 10, a member 20 secured to the trouser waistband 22 and a third member 25 adapted to connect the first two members.

The member 15 comprises a flat plate, preferably metal suitably plated, having a stud 16 projecting outwardly therefrom with a head 18 spaced from the plate. The plate 15 may be perforated at the corners as at 17 or otherwise recessed to permit it to be sewed or otherwise secured to the end of the web 10.

The member 20 may consist of a thin strip 70 or loop preferably metal, having openings 21 at each end whereby it may be secured to the waistband 22 of the trousers.

For connecting the members 15 and 20 I provide the member 25 which comprises a 75 clip preferably consisting of an endless wire bent in the manner shown in Fig. 3 to form an eye 26, a restricted or neck portion 27 and an upwardly bent hook 28.

In use the webs 10 are placed over the 80 shoulders in the position illustrated, under the shirt, the studs 16 on the plate 15 extending outwardly from the body. The wide portion of the clip 25 below the neck 27 is then slipped downwardly over the stud 85 16 which is covered by the fabric 13 of the shirt thereby pinching a tuft of the latter between the neck 27 and shank 16 of the stud. The head 18 covered by the shirt fabric is larger than the eye 26 which will 90 then embrace the shank 16, and thus prevents removal of the member 25 except by lifting off the stud 16 in the reverse manner from that in which it was applied. The lower hook portion 28 of the clip 25 is then 95 slipped underneath the strip 20 on the trouser waistband and there held by the elasticity of the cloth of the band. I have thus securely attached the webs 10, the shirt 13 and trousers 22, by means entirely concealed, 100 as will be apparent from the showing in Figs. 1 and 5, in an inexpensive, strong and practical manner.

I claim:

1. In a garment support a pair of suspender and means for attaching the ends of the same to the garments of the wearer, comprising plates having headed studs projecting therefrom sewed to the ends of the webbing of the suspenders, strips sewed to 110

the garment, and independent metal clips adapted to connect said studs with said strips.

2. In a trouser support, a suspender web, 5 means for connecting the same to the shirt and trousers of the wearer, comprising a flat strip or loop permanently secured to the waistband of the trousers, a headed stud permanently secured to the end of the sus-

pender web and a continuous bent wire 10 metal clip having a hooked end adapted to detachably engage said strip and an eye or loop at the other end adapted to grip the fabric of the shirt over the headed stud.

In testimony whereof I hereunto affix my 15 signature.

CLARENCE A. BUCHHOLZ.
